UNITED STATES PATENT OFFICE.

JOSEPH KOMOROUS, OF CHICAGO, ILLINOIS, ASSIGNOR TO PARISIAN NOVELTY COMPANY, OF CHICAGO, ILLINOIS, A CORPORATION OF ILLINOIS.

COIN-GUARD.

1,280,243.

Specification of Letters Patent. Patented Oct. 1, 1918.

Application filed April 8, 1916. Serial No. 89,927.

To all whom it may concern:

Be it known that I, JOSEPH KOMOROUS, a citizen of the United States, residing at Chicago, in the county of Cook and State 5 of Illinois, have invented a new and useful Improvement in Coin-Guards, of which the following is a specification.

My invention relates, more particularly, to coin-guard for savings banks of the 10 small, portable type and preferably adapted to be carried about in a person's pocket and into which coins may readily be inserted and be withdrawn therefrom upon opening the bank. My invention further relates, 15 more particularly, to banks in which the coin-slot through which the coins are introduced into the bank, is of a size adapting of the insertion therethrough of different sized coins, as for example quarters, nickels 20 and dimes.

As banks of this type have hitherto been constructed the smaller coins are easily withdrawn from the bank through the coin-slot, by spreading the coin-guards thereof 25 by means of wires, knife-blades and the like objects, thus frustrating the main object of the bank.

My primary object is to provide an improved construction of coin-guard whereby 30 the above-stated objection is avoided and coins inserted into the bank cannot be withdrawn therefrom through the coin-slot.

Referring to the accompanying drawing wherein I have shown my invention as applied to a bank of a general form commonly used—

Figure 1 is an edge view of the bank. Fig. 2 is an enlarged section taken at the line 2 on Fig. 1 and viewed in the direction 40 of the arrow. Fig. 3 is a view similar to Fig. 1 with the cover-section removed and showing a coin extending into the coin-slot.

Fig. 4 is a section taken at the line 4 on Fig. 2 and viewed in the direction of the 45 arrow with the cover-section removed. Fig. 5 is an enlarged broken section taken at the line 5 on Fig. 4 and viewed in the direction of the arrow. Fig. 6 is a broken plan view of the structure of Fig. 4. Fig. 7 is a perspective view of a guard-retaining frame employed; and Fig. 8, an enlarged face view of the coin-guard alone showing it in the 50 position it assumes when incorporated with the other parts of the bank.

55 The particular form of bank in connec-

tion with which I have chosen to illustrate my invention is of the type employing a pair of disks 9 and 10 and a band-section 11 interposed between them. The disk 10 which forms the bottom of the bank is permanently connected with the band-section 11 in accordance with common practice and the disk 9, which forms a cover, would be releasably connected with the band-section in any suitable way (not shown), this feature not forming any part of my present invention.

The coin-insertion slot of the bank is contained in the band-section 11 and is represented at 11^a, this slot in the particular construction shown being of sufficient dimensions to permit a quarter to be inserted through it into the receptacle portion of the bank formed between the covers 9 and 10 and band-section 11.

My improved coin-guard is located adjacent the inner side of said slot and in its preferred form comprises a pair of members 12 of springy material, such as brass-wire, these members being so formed, as shown, as to extend into contact at their central portions, as indicated at 13, and preferably at their ends as represented at 14 and 15, the portions of these members between these contacting points being deflected in opposite directions to space them apart, as represented. The members 12, which extend against the inner surface of the portion of the band-section 11 containing the slot 11^a, are curved to conform, in general, to the contour of the band 11 and are held against displacement with the portions thereof contacting at 13 extending midway of the ends of the slot 11^a, by a retaining member or cage 16. This cage is 90 in the form of a segment of a ring and has upper and lower flanges 17 and 18, end-flanges 19 and outwardly-projecting lugs 20 at opposite ends of a slot 21 which registers with, and is somewhat larger than, the coin-slot 11^a in the band-section 11. The cage 16 fits within the channel formed by the disks 9 and 10 and band-section 11 and bears at its upper flange 17 against the inner surface of the band-section 11 in which 95 position it is held by lugs 22 struck downwardly from the inwardly-extending annular flange-portion 23 of the band-section 11, between which lugs the cage 16 extends 100 (Fig. 2).

105 110

The members 12 are of such length that their ends reach substantially to the inner surfaces of the flanges 19 and are of such shape that they extend at their diverging portions above and below, and preferably in contact with, the upper and lower edges of the lugs 20, the members 12 being preferably so formed that when they are assembled with the other parts of the structure they will be under spring-tension tending to draw them together at the point indicated at 13, thus pressing them together at this point and furnishing the most desirable resistance to their separation, the lugs 20 preventing them from springing past each other and holding them normally in centralized position opposite the slot 11^a. The members 12 are furthermore so shaped and proportioned, as shown, that the only portions thereof in contact with each other which register with the slot 11^a, are those which are represented in contact at 13, as shown in Fig. 1, and the divergent parts of the members 12 are disposed at such an angle to each other and relative to the slot 11^a, as shown, that it is not possible by inserting a wire, blade, or the like, into the slot 11^a and between the members 12, to pry them open a sufficient distance to permit a coin even as small as a dime to be withdrawn through the slot 11^a, though this slot may be large enough to receive a quarter.

It will be understood from the foregoing that in inserting a coin, as for example the dime shown at X, into the bank through the slot 11^a, the coin presses the members 12 apart and when the coin has passed through these members they spring back to normal position, wherein they prevent withdrawal of the coins from the bank.

While I have illustrated and described a certain form of coin-guard embodying my invention, I do not wish to be understood as limiting it thereto, as the same may be variously modified and altered without departing from the spirit of my invention. Furthermore, I do not wish to be understood as limiting it to use in connection with the particular form of bank shown.

What I claim as new and desire to secure by Letters Patent is:—

1. In a bank, the combination with a receptacle having a coin-slot, of means for preventing the withdrawal of coins through said slot comprising resilient members of wave-like form, parts of which extend into relatively close proximity to each other at approximately the center of the width and length of said slot and in close proximity to said slot to normally close the same, the spaces flanking such central opposing portions being of less width than the diameter of a coin.

2. In a bank, the combination with a re-

ceptacle having a coin-slot, and means for preventing the withdrawal of coins through said slot formed of a pair of undulating spring wires extending and closely adjacent to said opening and partially closing the same, and a plate forming with the wall of the bank a housing for said means. 70

3. In a bank, the combination of a receptacle containing a coin-slot, and means for preventing the withdrawal through said slot of coins in said receptacle, comprising an undulatingly formed spring device which is positioned to extend lengthwise of said slot and normally extends in coin-obstructing position and is movable perpendicular to the slot against its tendency to return to normal position, to permit of the insertion of a coin into said receptacle, said receptacle containing a housing in which said spring device is mounted. 75

4. In a bank, the combination of a receptacle containing a coin-slot, and means for preventing the withdrawal through said slot of coins in said receptacle, formed of a pair of undulatingly formed spring wires 90 positioned to extend lengthwise of said slot and normally in coin-obstructing position and movable substantially perpendicular to the slot against a tendency to return to normal position, to permit of the insertion of a coin into said receptacle, said receptacle containing a plate forming with the wall of said receptacle, a housing in which said wires are mounted. 95

5. In a bank, the combination of a receptacle containing a coin-slot, and means for preventing the withdrawal through said slot of coins in said receptacle, comprising undulatingly formed spring wire positioned to extend lengthwise of said slot and normally in coin-obstructing position and movable substantially perpendicular to the slot against a tendency to return to normal position, to permit of the insertion of a coin into said receptacle, said receptacle containing a housing in which said spring wires are mounted, and guidedly confining the same in their movement. 105

6. In a bank, the combination of a receptacle containing a coin-slot, and means for preventing withdrawal through said slot of coins in said receptacle formed of spring-members which are positioned to extend lengthwise of said slot and normally extend in coin-obstructing position, said spring-members extending into close proximity to each other intermediate only the ends of said slot and movable perpendicular to the slot against their tendency to return to normal position, to permit of the insertion of a coin 115 into said receptacle. 120

7. In a bank, the combination of a receptacle containing a coin-slot, and means for preventing withdrawal through said slot of coins in said receptacle formed of a pair 130

of spring-members positioned to extend lengthwise of said slot, said spring members opposing each other and having portions offset relative to adjacent parts of said spring-
5 members at which the latter extend into close proximity opposite said slot, but at a point intermediate only the ends of said slot, whereby the portions of said spring-members adjacent the ends of said slot do
10 not extend across the latter, said spring-members normally extending in coin-obstructing position and movable perpendicular to the slot against their tendency to return to normal position, to permit of the
15 insertion of a coin into said receptacle.

8. In a bank, the combination of a receptacle containing a coin-slot, means for preventing withdrawal through said slot of coins in said receptacle, including coin-
20 guard members, extending lengthwise of said slot adjacent opposite sides thereof and normally extending into close proximity to each other intermediate only the ends of said slot, and movable in a direction cross-
25 wise of said slot, and a member secured in said receptacle between which and said receptacle said coin-guard-members extend, and provided with lugs interposed between said coin-guard-members at opposite sides of the
30 portions of said coin-guard-members which extend into close proximity to each other.

9. In a bank, the combination of a receptacle containing a coin slot, and means

for preventing the withdrawal through said slot of coins in said receptacle comprising a 35 spring device parts of which extends closely adjacent the said slot and partially close the same in the normal position of the structure, said spring device being movable in a plane perpendicular to the line of movement of 40 the coin in entering said slot.

10. In a bank, the combination of a receptacle containing a coin slot, and means for preventing the withdrawal through said slot of coins in said receptacle including 45 coin guard members extending lengthwise of said slot adjacent opposite sides thereof and normally extending into close proximity into each other intermediate only the ends of said slot and movable in a direction cross- 50 wise of said slot, whereby said members can be separated only by an object introduced between them into the path of movement of the coins through said slot.

11. In a bank, the combination of a receptacle having a coin-slot, of resilient means for preventing the withdrawal of coins through said slot and extending approximately to the center of the width and length of said slot and in close proximity to said slot and acting with an opposed edge of said slot to normally close the same, the spaces flanking such resilient means being of less width than the diameter of a coin. 55 60
